FREE-STANDING INDOOR STOVE

Manfred J. Weber and Dennis W. Rothe, Brookfield,
Gerald Kopke, New Milford, and Paul W. Weber,
Ridgefield, Conn., assignors to Construction Products,
Inc., Brookfield, Conn.

Filed Mar. 11, 1974, Ser. No. 449,925

Term of patent 14 years

Int. CL. D23—03

U.S. CL. D23—97

FIG. 1

FIG. 2

FIG. 3

FIG. 4

FIG. 5

FIG. 6

FIG. 7

FIG. 1 is a perspective of a free-standing indoor stove according to our design.

FIG. 2 is a front elevational view thereof.

FIG. 3 is a left side elevational view thereof.

FIG. 4 is a right side elevational view thereof.

FIG. 5 is a rear elevational view thereof.

FIG. 6 is a top plan view thereof.

FIG. 7 is a bottom plan view thereof.

We claim:

The ornamental design for a free-standing indoor stove, substantially as shown and described.
